UNITED STATES PATENT OFFICE.

RAYMOND M. HATCH, OF TRUMANSBURG, NEW YORK.

NUT LOCK.

1,416,292.

Specification of Letters Patent. Patented May 16, 1922.

Application filed August 23, 1920. Serial No. 405,269.

To all whom it may concern:

Be it known that I, RAYMOND M. HATCH, a citizen of the United States of America, residing at Trumansburg, in the county of 5 Tompkins and State of New York, have invented certain new and useful Improvements in Nut Locks, of which the following is a specification.

The primary object of the invention is the 10 provision of a nut lock adapted for employment with both wood and metal, whereby the nut is prevented from becoming accidentally loosened when the device is in use although the nut may be removed from the 15 bolt when desired, the surface of the material being held by the bolt being substantially undamaged, or mutilated by repeated use of the device.

A further object of the invention is the 20 provision of a form of cooperating nut and lock washer adapted for repeated use upon an ordinary form of bolt without injury to any of the parts, a single wrench being employed for readily removing the nut when in 25 its locked position although the latter is prevented from jarring or working loose when once positioned upon the work.

A still further object of the invention is the provision of a nut lock that is simple in 30 construction, easy and inexpensive to manufacture and capable of universal use wherever such a device is desirable for use upon bolts, such for instance as motor vehicles, the device being readily operable to its locking 35 position as well as releasable when occasion requires.

With these general objects in view, the invention consists of the novel combination and arrangement of parts hereinafter more 40 fully described in connection with the illustrations of the accompanying drawing and in which like reference characters designate corresponding parts throughout the several views.

45 In the drawing,

Figure 1 is a plan view of a piece of material showing my invention operatively positioned upon a bolt secured therethrough,

Figure 2 is a side elevation thereof partially broken away,

Figure 3 is a transverse sectional view of the same with the lock washer broken away,

Figure 4 is a plan view of the outer face of the lock washer and

55 Figure 5 is an edge view thereof with the inner face uppermost.

Referring more in detail to the drawing, my invention broadly consists of a lock washer 10 and a substantially usual form of threaded nut 11 having its inner face adapted for cooperating with the washer when positioned upon the screw threads 12 of a usual form of bolt 13. The bolt 13 is herein illustrated in use extending through openings 14 and 15 provided in two pieces of material 16 and 17 respectively of wood, metal, or the like, it being understood that the head 18 at one end of the bolt 13 is preferably socketed in the material being held or otherwise prevented from turning in any desired 70 manner.

The washer 10 has one or more notches 19 sloping in the same direction annularly of its inner face and herein illustrated as two in number, forming teeth 20 adapted for engaging the outer surface 21 of the work or adjacent block 17. The opposite outer face of the washer 10 has similar notches 22 forming ratchet teeth or shoulders 23 adapted for engagement by similar teeth 24 upon the inner end of the nut 11. The teeth 24 of the nut are preferably the same in number as the teeth 23 upon the outer face of the washer 10 with the adjacent faces of the nut and washer complementally formed for close 85 engagement with each other when the device is normally positioned locked upon the bolt 13. The number of work engaging teeth 20 may or may not be the same as that of the nut engaging teeth 23 of the washer 10 while 90 one or any greater number of such teeth will serve to carry out the objects of my invention.

With the bolt 13 positioned through the blocks 16 and 17 to be held, the washer 10 95 is positioned upon the bolt 13 with the teeth 20 against the outermost block 17 while the nut 11 is then screwed upon the threads 12 for engaging the shoulders 24 of the nut with the teeth 23 at the outer 100 side of the washer as best illustrated in Figure 3 of the drawing.

The nut 11 is then tightened upon the bolt and when the shoulders 24 engage the teeth 23, the washer 10 will turn upon the bolt 13 105 with the nut 11 while the teeth 20 upon the inner face of the washer 10 will be forced around upon the outer face 21 of the block 17, sinking into the block as the nut 11 assumes its tightened position. Any 110 attempt to remove the nut 11 by reversing the direction of revolution causes the inner

face of the nut to ride upwardly on the teeth or shoulders 23 of the washer 10 making the turning of the nut extremely difficult and preventing accidental loosening or removal of the nut by reason of the engagement with the washer 10 heretofore described.

By applying a wrench to the nut 11, however, the same may be turned off of the 10 threaded portion 12 of the bolt as the teeth 20 of the washer 10 prevent the turning of the washer during the removal of the nut so that the nut ratchets over the washer teeth 23 and while the initial removing 15 movement tightens the nut upon the washer, the engagement therebetween is lessened as soon as the nut teeth 24 pass the first succeeding tooth 23 of the washer. Thereafter, the nut 11 is readily removed from the bolt 20 and it will be understood that the angle or pitch of the ratcheting engagement between the adjacent faces of the nut 11 and washer 10 is greater than that of the threads of the portion 12 of the bolt 13. While the 25 preferred form of the invention is herein

set forth, it will be understood that minor changes may be made therein without departing from the spirit and scope of my invention.

A washer 10 or a plurality thereof may 30 also be used in connection with an ordinary bolt and threaded nut if desired although the form of nut 11 is found desirable. My nut lock may be released by the employment of a single wrench.

What is claimed as new is:

The combination with a nut having a pair of diametrically disposed teeth on its under side facing in the direction of rotation in screwing the nut on a bolt, of a locking washer therefor having a pair of teeth on each side diametrically disposed, the teeth on each side facing in the opposite direction of rotation of the nut in screwing the same upon a bolt, the pitch of the teeth on opposite sides of the washer being of the same degree.

In testimony whereof I affix my signature.

RAYMOND M. HATCH.
